United States Patent Office.

CHARLES P. EAGER, OF BOSTON, MASSACHUSETTS, ASSIGNOR TO P. B. EAGER, OF SAME PLACE.

Letters Patent No. 97,896, dated December 14, 1869.

IMPROVED VENTILATING HORSE-COVER.

The Schedule referred to in these Letters Patent and making part of the same.

To all whom it may concern:

Be it known that I, CHARLES P. EAGER, of Boston, in the county of Suffolk, and State of Massachusetts, have invented a new and improved Ventilating Horse-Cover; and I do hereby declare that the following is a full, clear, and exact description thereof, which will enable others skilled in the art to make and use the same, reference being had to the accompanying drawings, forming part of this specification, in which—

Figure 1 represents a side view of my improved horse-cover.

Figure 2 is a vertical transverse section of the same.

Similar letters of reference indicate corresponding parts.

This invention relates to that class of horse-covers which is provided with a ventilating-top, and also made water-proof; and

It consists in the combination and construction of parts, as hereinafter set forth.

The invention also consists in the application of elastic straps to the cover, for fastening it to the body of the horse, and for holding the neck-cover to the body-cover.

The invention finally consists in applying to a water-proof cover of the aforesaid class, rings, for receiving the reins, in place of the straps heretofore obtained by the cutting of the fabric, whereby the cover was injured, and its water-proof quality destroyed.

The cover is made of a suitable number of sections, two being shown in the drawing, one, A, for covering the body, and the other, B, for the neck of the animal.

The several sections are connected by elastic straps, and are furthermore provided with other elastic straps *a a*, by which they are fastened to the horse and harness.

Where two sections come together, one has a flap, *b*, to cover the joint.

Every section consists of three, or more, or less, several pieces. In the drawing three are shown, one, *c*, in the middle, and the other, *d d*, at the sides.

The several pieces are connected with each other by triangular or other metallic or other rigid braces *e e*, which hold them apart, as shown, and therefore allow air to pass out between them.

Water is prevented from entering between the pieces *c d*, by the overhanging of the higher piece *c*, as shown in fig. 2.

The braces *e* are arranged at suitable distances apart, and are fastened by sewing, or otherwise.

f f are rings sewed upon the cover, for guiding the reins. They are, by sewing, so fastened that they will not be the cause of any water flowing under the cover.

The elastic straps on the cover will allow the same to yield to every motion of the horse, and without having any parts strained.

Hitherto the covers for horses have been provided with non-elastic straps, but these do not allow a free movement of the animal's head, and at the same time secure the desideratum of a close-fitting cover, or one that will constantly maintain its proper position without hanging over too much on one side or the other at the ends, as well as presenting a somewhat inelegant appearance by reason of the slack or fullness it is in that case necessary to give said cover.

To obviate these difficulties, I have applied the elastic straps *a* at front and rear, which allow the cover to yield to every motion of the horse without straining.

Having thus described my invention, I claim as new, and desire to secure by Letters Patent—

1. The horse-cover, composed of the sections A A and B, when connected longitudinally by the cover *c*, attached to the rigid braces *e e*, substantially as herein shown and described, for the purpose specified.

2. The horse-cover, provided with elastic straps, substantially as and for the purpose herein shown and described.

CHARLES P. EAGER.
